(57) **CLAIM**

The new and ornamental design for a mesh back task chair back and bottom with pelvic positioning, as shown and described.

DESCRIPTION

FIG. 1 is a perspective view of a mesh back task chair back and bottom with pelvic positioning showing my new design;

FIG. 2 is a view in front elevation of the mesh back task chair back and bottom with pelvic positioning of FIG. 1;

FIG. 3 is a view in rear elevation of the mesh back task chair back and bottom with pelvic positioning of FIG. 1;

FIG. 4 is a view in left side elevation of the mesh back task chair back and bottom with pelvic positioning of FIG. 1;

FIG. 5 is a view in right side elevation of the mesh back task chair back and bottom with pelvic positioning of FIG. 1;

FIG. 6 is a top plan view of the mesh back task chair back and bottom with pelvic positioning of FIG. 1;

FIG. 7 is a bottom plan view of the mesh back task chair back and bottom with pelvic positioning of FIG. 1;

FIG. 8 is a bottom plan view of the mesh back task chair back and bottom with pelvic positioning of FIG. 1 with the support base, which forms no part of the claimed design, removed for clarity;

FIG. 9 is a bottom plan view of the mesh back task chair back and bottom with pelvic positioning of FIG. 1 with the support base, control mechanisms, and arms, which form no part of the claimed design, removed for clarity;

FIG. 10 is a perspective view of a mesh back task chair back and bottom with pelvic positioning showing my new design with fixed-height arms, which form no part of the claimed design;

FIG. 11 is a view in front elevation of the mesh back task chair back and bottom with pelvic positioning of FIG. 10;

FIG. 12 is a view in rear elevation of the mesh back task chair back and bottom with pelvic positioning of FIG. 10;

FIG. 13 is a view in left side elevation of the mesh back task chair back and bottom with pelvic positioning of FIG. 10;

FIG. 14 is a view in right side elevation of the mesh back task chair back and bottom with pelvic positioning of FIG. 10;

FIG. 15 is a top plan view of the mesh back task chair back and bottom with pelvic positioning of FIG. 10;

FIG. 16 is a bottom plan view of the mesh back task chair back and bottom with pelvic positioning of FIG. 10;

FIG. 17 is a bottom plan view of the mesh back task chair back and bottom with pelvic positioning of FIG. 10 with the support base, which forms no part of the claimed design, removed for clarity; and,

FIG. 18 is a bottom plan view of the mesh back task chair back and bottom with pelvic positioning of FIG. 10 with the support base, control mechanisms, and arms, which form no part of the claimed design, removed for clarity.

The broken lines in the drawings are for illustrative purposes only and form no part of the claimed design. In addition, the particular mesh fabric of the chair back is shown for illustrative purposes only and forms no part of the claimed design.
